E. B. RICE.

SLOT ANGLE BAR.

APPLICATION FILED MAY 11, 1918.

1,303,726.

Patented May 13, 1919.

UNITED STATES PATENT OFFICE.

EARNEST B. RICE, OF GRAND SALINE, TEXAS.

SLOT ANGLE BAR.

1,303,726.

Patented May 13, 1919.

Application filed May 11, 1918. Serial No. 233,898.

To all whom it may concern:

Be it known that I, EARNEST B. RICE, a citizen of the United States, residing at Grand Saline, in the county of Van Zandt 5 and State of Texas, have invented certain new and useful Improvements in Slot Angle-Bars; and I do hereby declare the following to be a full, clear, and exact description of the invention, such as will enable others skilled in the art to which it appertains to make and use the same.

This invention relates to rail joints and the primary object of the invention is to provide an improved means for uniting the 15 meeting ends of rail sections without the use of nuts and bolts and the like.

Another object of the invention is to provide an improved rail joint, having means for uniting the meeting ends of the railroad 20 rails together, and means for locking the same against movement in relation to the rail chair, which receives the meeting ends.

A further object of the invention is to 25 provide an improved railroad chair for receiving the meeting ends of the rail sections, which is provided with a slot for receiving the means employed for uniting the rail sections together, this slot having a groove 30 communicating therewith which is adapted to receive a locking key to engage said means, to prevent movement thereof.

A still further object of the invention is 35 to provide an improved device of the above character which is durable and efficient in use, one that is simple and easy to manufacture and one that can be placed upon the market at a reasonable cost.

With these and other objects in view the 40 invention consists in the novel construction, arrangement and formation of parts, as will be hereinafter more specifically described, claimed and illustrated in the accompanying drawing forming a part thereof in which:

Figure 1 is a plan view of the improved 45 rail joint,

Fig. 2 is a cross section taken on the line 2-2 of Fig. 1,

Fig. 3 is a horizontal longitudinal section 50 taken through the improved rail joint,

Fig. 4 is a fragmentary detail perspective view of the rail chair, and

Fig. 5 is a detail perspective view of the locking key.

Referring to the drawings in detail, 55 wherein similar reference characters desig-

nate corresponding parts throughout the several views, the numeral 1 generally indicates the improved rail chair, which is adapted to receive the meeting ends of the 60 rail sections 2 and 3.

The improved rail chair is constructed from one piece of suitable metallic material and consists of a base for supporting the base of the rail, and upwardly extending 65 sides 5 and 6, the inner faces of which are formed to the contour of the base and web of the rail sections.

The rail sections 2 and 3 are provided with transverse apertures 7, which are positioned adjacent to the ends thereof and the apertures arranged to receive the legs 8 of the U-shaped locking member 9, the bight portion 10 of which is adapted to lie against the webs of the rail sections.

The inner face of the side 6 is provided 70 with a groove 11 which extends inwardly from one end wall thereof to a point beyond the center of the chair.

In assembling the improved device, one 80 leg of the U-shaped member 9 is positioned in the aperture 7 of the rail section 3, which is slid into the chair 1 until the same protrudes out of the operative end thereof, the leg 8 of the U-shaped member 9 is then positioned in the aperture 7 of the rail section 2 and the rail sections are then slid into the chair and the bight portion 10 of the U-shaped member 9 slides into the groove 11, which is provided for that purpose.

To prevent displacement of the rail sections 2 and 3 in relation to the rail chair 1, a key 12 is provided, which is adapted to sit in a slot 13, which extends downwardly from the upper surface of the chair to a 95 point below the groove 11. The groove 13 is spaced from the end wall of the groove 11, so that the bight portion 10 of the U-shaped member 9 will rest between the end wall and the groove 13.

The key 12 includes the straight body portion 13' having the lower end thereof offset as at 14, which is adapted to sit in the lower contracted portion 15 of the groove 13 and sits behind and engages the U-shaped member 9, so as to confine the same between the rear wall of the groove 11 and the key. The upper end of the key is provided with a head 16, which provides means whereby the same can be removed when desired.

In practice, I have found that the form of my invention, illustrated in the accom-

panying drawings and referred to in the above description, as the preferred embodiment, is the most efficient and practical; yet realizing the conditions concurrent with the adoption of my device, I desire to emphasize the fact that various minor changes in detail of construction, proportion and arrangement of parts may be resorted to, when required, without sacrificing any of the advantages of my invention as set forth.

What I claim as new is:

1. In a device of the class described, the combination, of a pair of rails, a U-shaped locking member arranged to lock the rails together, of a chair arranged to slidably receive the rails and the U-shaped locking member, and a vertically sliding key detachably carried by the chair intermediate the ends thereof and arranged to engage the U-shaped locking member to prevent relative movement between the rails and chair.
2. A device of the class described the com-

bination, of a pair of rails having apertures therein adjacent to the meeting ends, thereof, a U-shaped member having parallel legs arranged to fit in the apertures to unite the sections together, of a chair arranged to receive the rail sections, the chair having a groove extending from one end thereof to a point beyond the center thereof arranged to slidably receive the bight portion of the U-shaped member, the chair having a groove communicating with the first groove and extending at right angles thereto, and a key arranged to fit in the last mentioned groove and engage the U-shaped member, as and for the purpose specified.

In testimony whereof I affix my signature in presence of two witnesses.

EARNEST B. RICE.

Witnesses:

W. Z. CRAFFORD,
A. C. DAVIS.
